UNITED STATES PATENT OFFICE.

EMILE BICK, OF NEW HAVEN, CONNECTICUT.

DESIGN FOR A HEADPIECE FOR GRAVES.

SPECIFICATION forming part of Design No. 33,602, dated November 20, 1900.

Application filed October 27, 1900. Serial No. 34,669. Term of patent 7 years.

To all whom it may concern:

Be it known that I, EMILE BICK, a citizen of France, residing at New Haven, in the county of New Haven and State of Connecticut, have 5 invented and produced a new and original Design for a Headpiece for Graves, of which the following is a specification, reference being had to the accompanying drawings, forming part thereof.

Figure 1 is a perspective view of the headpiece embodying my design, and Fig. 2 is a cross-section on line 2 2 of Fig. 1.

The leading features of the design are the cruciform shape of the upper portion of the headpiece, the provision of circular recesses *a* in the horizontal arms *b* and in the head of the vertical portion or body *c*, and the pyramidal form of the point or lower end of such body.

Minor features of the design are four horizontal arms or bars *e*, radiating from the lower portion of the body *c*, and a rectangular panel *f*, arranged above said bars. 20

Having described my invention, what I claim as new, and desire to secure by Letters Patent, is—

The design for a headpiece for graves, substantially as shown and described.

In testimony whereof I have signed my name to this specification in the presence of two subscribing witnesses.

EMILE BICK.
